United States Patent

Des. 240,302
Patented June 15, 1976

240,302

POLE TELEPHONE

Douglas P. Montague, Chicago, and Howard J. Morrison,
Deerfield, Ill., assignors to Marvin Glass & Associates,
Chicago, Ill.

Filed Sept. 30, 1975, Ser. No. 618,071

Term of patent 14 years

Int. Cl. D14—03

U.S. Cl. D26—14 A

FIG. 1 is a perspective view of a pole telephone embodying the design of our invention;

FIG. 2 is a front elevational view thereof;

FIG. 3 is a side elevational view thereof, the opposite side being substantially identical thereto;

FIG. 4 is a rear elevational view thereof;

FIG. 5 is a top plan view thereof; and

FIG. 6 is a bottom plan view thereof.

We claim:

The ornamental design for a pole telephone, as shown and described.
